(57) **CLAIM**

The ornamental design for a headset and charging base set, as shown and described.

DESCRIPTION

FIG. 1 is a perspective view of a headset of a headset and charging base set showing my new design shown separately for ease of illustration;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of a charging base of the headset and charging base set shown separately for ease of illustration;

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof; and,

FIG. 17 is a perspective view of the headset and charging base set where the headset is held by the charging base. The broken lines in the drawings depict portions of the headset and charging base set that form no part of the claimed design.

1 Claim, 17 Drawing Sheets
